Ralph K. Boyer, Cleveland, Ohio, assignor to The
Dill Manufacturing Company, Cleveland, Ohio,
a corporation of Ohio

Application March 27, 1952, Serial No. 19,077

Term of patent 14 years

(Cl. D90—20)

To all whom it may concern:

Be it known that I, Ralph K. Boyer, a citizen of the United States, residing at Cleveland, and State of Ohio, have invented a new, original, and ornamental Design for a Tire Valve Stem Cap, of which the following is a specification, reference being had to the accompanying drawing, forming a part thereof, in which:

Fig. 1 is an elevational view of a tire valve stem cap showing my new design.

Fig. 2 is a top plan view thereof, and

Fig. 3 is a section on the line 3—3 of Fig. 1.

I claim:

The ornamental design for a tire valve stem cap, substantially as shown.

RALPH K. BOYER.
